PROJECTILE

Ralph W. Hippen, Hobart, Okla.

Application January 4, 1939, Serial No. 249,208

4 Claims. (Cl. 46—86)

This invention relates broadly to projectiles and other devices of similar character and in certain of its aspects is in the nature of an improvement over the projectile disclosed in Hippen and Barnes Patent No. 2,060,213. The projectile disclosed in said patent is of the type adaptable for use as a toy, being generally in the shape of an airplane and comprising an openable casing containing a parachute. The casing sections are hinged together and a latch is provided for maintaining the casing closed. A gravity actuated ball or the like separate from the latch is adapted to roll down an incline and strike the latch to move it to inoperative position when the projectile assumes a predetermined position in flight. This allows the casing to open and the parachute to come out and the fall of the projectile is retarded by the parachute.

Projectiles of the type disclosed in said patent, and especially those made for the toy trade, must be of as rugged and foolproof construction as possible and of very low cost. This field is very highly competitive and the difference of a fraction of a cent per unit in cost may mean the difference between a successful commercial product and an unsuccessful one. I have found that although the projectile disclosed in said patent is satisfactory in workmanship and operation its cost is so high that it does not occupy as favorable a position as its merit warrants in the toy field which is so highly competitive pricewise. I have improved upon the projectile disclosed in said patent by greatly simplifying its structure while still obtaining the same results and my new projectile is much lower in cost and there is practically no likelihood of its getting out of order.

I have found that I can considerably lighten the weight of the projectile, thus enabling it to be made of lighter material, by eliminating the large latch actuating ball and its guiding tube and providing instead gravity actuated means carried by the latch. Such means can function effectively when of comparatively small mass and I have found that by having the same carried by the latch the amplitude of movement thereof may be comparatively small, thus reducing the size of the cooperating parts. I have found that when the parts are properly designed and constructed it is only necessary to impart to the latch sufficient force to overcome the friction between the latch and the keeper with which the latch cooperates to hold the casing closed, after which the latch swings open of its

own accord. Thus I am enabled to reduce to a minimum the size and amplitude of movement of the gravity actuated means which is carried by and acts upon the latch.

5 I have made a further improvement over the projectile disclosed in said patent which is also important from the standpoint of cost of manufacture. In place of the knuckle hinge construction used for holding the casing parts together 10 in said patent I provide a novel and very simple hinge connection the parts of which can be made integral with the respective parts of the casing, as, for example, in a stamping operation. I provide interengageable projection and recess 15 means on the respective casing parts which remain normally in interengagement and are movable to and from their interengaged position only upon deformation of the material of at least one of the casing parts. This feature is adaptable for the connection of any two parts at least one of which is of deformable material, and its utility is not limited to projectiles.

Other details, objects and advantages of the invention will become apparent as the following description of certain present preferred embodiments thereof proceeds.

In the accompanying drawings I have shown certain present preferred embodiments of the invention, in which—

30 Figure 1 is a perspective view of a projectile; Figure 2 is a side view of the projectile shown in Figure 1;

35 Figure 3 is a transverse cross-sectional view of the projectile shown in Figures 1 and 2 taken on the line III—III of Figure 2;

Figure 4 is a detail view of a portion of the projectile shown in Figures 1, 2 and 3, showing the latch in operative position with the projectile moving generally upwardly;

40 Figure 5 is a view similar to Figure 4 showing the latch in inoperative position with the projectile moving generally downwardly;

Figure 6 is a view of the inside of one of the casing parts when such parts are disassembled;

45 Figure 7 is a view similar to Figure 6 of the other casing part but in inverted position so that the parts as shown in Figures 6 and 7 are as they would lie if disassembled and laid back away from each other;

50 Figure 8 is a perspective view of the projectile showing the parachute released;

Figures 9 and 10 are views similar to Figures 3 and 4, respectively, but showing a modified form of structure; and

55 Figure 11 is an elevational view showing the

projectile falling with the parachute operative.

Referring now more particularly to the drawings, I provide a projectile having generally the shape and flight characteristics of an airplane and comprising a body 2 made up of opposed halves 3 and 4, respectively. Each of the halves or sections of the projectile carries a wing or airfoil 5 and an elevator 6. The section 4 carries a rudder 7. The parts of the projectile just described are preferably made of light weight cheap sheet material. While thin sheet metal may be employed I have found Celluloid and similar synthetic materials to be highly suitable, as such materials are low in cost, light in weight and of pleasing appearance. The particular projectile from which the patent drawings were made was constructed of Celluloid with the wings and elevators formed separately from the sections of the body and adhesively connected therewith, the rudder being stamped out integrally with the casing section 4, which reduces the cost of the device.

Each of the casing sections is of generally elongated hollow shape, as shown in Figures 6 and 7. The casing section 3 carries as an integral portion thereof a supporting member 8, through which passes a pivot member 8'. Carried for pivotal movement about the pivot 8' in the casing section 3 is a latch 9 having a latching projection 10 adapted to engage a keeper 11 on the section 4 to maintain the casing closed when the latch is in operative position, as will presently be explained. Connected with the latch 9 is an elongated cage 12 containing a small body or weight adapted during operation of the device to be actuated by gravity, as will presently be described. Such small body or weight is illustrated as in the form of a lead ball 13 and may be, for example, an ordinary BB shot. It is confined within the elongated cage 12 and is movable 40 therein during operation of the device, as will be described.

There is provided a parachute 14 connected with the projectile by a line 15 which passes through an eye 16 in the casing section 4 and is 45 tied to the casing section 3 through an eye 17 therein.

Stamped out integrally with the casing section 3 is a pair of spaced projections 18 each having at its edge most remote from the other projection a hook 19 facing away from the other projection. The casing section 4 has a pair of spaced recesses or slots 20 shaped to receive the projections 18 when the parts are assembled. The projections 18 are, however, spaced apart slightly farther than the recesses 20 so that to enable assembly of the parts it is necessary to bend or otherwise deform the section 3 to bring the projections slightly closer together or to stretch or otherwise deform the section 4 to 60 slightly increase the distance between the recesses, whereupon the projections 18 may be inserted within the respective recesses 20. The parts after assembly assume their normal condition and the hooks 19 interengage with the material at the edges of the recesses 20 most remote from each other, as shown in Figure 2. When the casing sections are made of material such as Celluloid or very light gauge sheet metal it is not difficult to bend the section 3 sufficiently to 70 enable the projections 18 to enter the recesses 20. The difference in spacing of the projections 18 and the recesses 20 is only approximately as great as the sum of the depths of the throats of the hooks 19. In assembling the casing sections 75

preferably one of the hooks 19 is interengaged with the corresponding recess 20, thus making it necessary to deform one of the casing sections only sufficiently to bring the projections closer together or separate the recesses a distance approximately equal to the depth of the throat of the other hook. The projectile shown in the drawings is drawn roughly to full scale and in such projectile the depth of the throat of each of the hooks 19 is approximately 1/16".

The operation of the device will now be described and in connection with the description thereof the relationship and functioning of the parts will be more clearly understood. In preparing the projectile for use the parachute is folded in such manner that upon opening of the casing it may readily be discharged therefrom so as to open and support the casing during falling and is then inserted into the casing, preferably with the line 15 beneath it, so that when the casing opens the line will not be in the way and will permit proper release and opening of the parachute. Before closing the casing it is held with the nose downwardly so that the latch is in inoperative position, as shown in Figure 5. The latch itself tends to swing to such position about the pivot 8 due to gravity when the casing is held with its nose downwardly. When the parachute has been properly inserted the casing sections are closed and the casing is then tilted back to the position shown in Figures 2 and 4, the latch moving due to gravity into operative position with its latching projection 10 engaging the keeper 11 to maintain the casing closed. When the casing is in this position the ball 13 moves to the rear of the cage 12, as shown.

The projectile is projected by any suitable means, such, for example, as a slingshot having a resilient projecting device, such as a rubber band, which is adapted to be received by the hook 21 at the nose of the casing and formed as a continuation of the rudder 7. The projectile is drawn back to stretch the rubber band and is then let go and projected by the rubber band up into the air. The projectile is preferably projected upwardly at at least a moderately steep angle, although the angle may be varied as desired. During upward movement of the projectile the ball 13 is maintained at the rear end of the cage 12 and the latch 9 is maintained in operative position by gravity and inertia. The rudder tends to maintain the projectile on a straight course and as the projectile nears the apex of its flight it tends by reason of being somewhat heavy in the nose and by reason of its design to simulate an airship to level off and fly, at least for a time, generally horizontally rather than immediately turning its nose downwardly and plummeting to the ground. The wings 5 are, as shown in the drawings, made as airfoils tending to counteract to a certain extent at least the tendency of gravity to turn the nose of the projectile downwardly. Thus the force of gravity is counteracted by the wings at least to a sufficient extent to cause the casing to hover in the air or move generally horizontally corresponding to the position in which the casing section 3 is shown in Figure 6. When the upward inclination of the casing diminishes as the projectile tends to level off and the casing assumes approximately the position of the casing section 3 in Figure 6 the ball 13 rolls from the back to the front of the cage 12 due to gravity and strikes the front of the cage. As the cage is carried by the latch this imparts to the latch a force tending to move the

latch counter-clockwise, viewing Figure 6, about the pivot 8'. This force is sufficient to overcome the friction between the latch and the keeper, and the latch with such friction overcome moves by gravity to the inoperative position, as shown in Figures 5 and 6. When the latch moves to inoperative position the ball 13 may move back to the rear end of the cage 12 if the casing does not nose downwardly very quickly. Thereafter as the casing noses more steeply downwardly before the parachute takes effect the ball may return to the forward end of the cage as shown in Figure 5. This, however, is immaterial as the ball has served its purpose upon its first movement above described from the rear to the forward end of the cage when its striking against the forward end of the cage imparts to the latch sufficient force to overcome the friction between the latch and the keeper, allowing the latch to swing by gravity to inoperative position.

When the latch moves to inoperative position, as shown in Figures 5 and 6, the casing opens and the parachute comes out and opens up. As the line 15 passes through the eye 16 in one of the casing sections and is connected to the other casing section it causes the casing to close and the casing falls to earth supported by the parachute, as shown in Figure 11.

There is shown in Figures 9 and 10 a modified form of structure in which the ball 13 and the cage 12 are replaced by a slot 22 in the latch (which is designated 9') and a double headed button or rivet 23 is slidably mounted in the slot 22 for movement longitudinally of the slot and whose function is precisely the same as the function of the ball 13 as it moves in the cage 12 in the structure shown in Figures 2 to 7, inclusive. Figures 1, 8 and 11 show the device generally and so far as these figures are concerned the latch actuating means may be either the ball or the 40 double headed button or rivet.

While I have shown and described certain present preferred embodiments of the invention, it is to be distinctly understood that the same is not limited thereto but may be otherwise variously embodied within the scope of the following claims.

I claim:

1. A projectile comprising an openable casing, latch means normally maintaining the casing closed, and means carried and guided solely by the latch means gravity actuated upon movement of the casing to a predetermined position insuring movement of the latch means to inoperative position.

2. A projectile comprising an openable casing, latch means normally maintaining the casing closed, and a weight carried by and movable relatively to the latch means and adapted to strike a portion of the latch means to insure movement of the latch means to inoperative position.

3. A projectile comprising an openable casing, latch means connected with one portion of the casing adapted normally to engage another portion thereof to maintain the casing closed, and a weight carried by and movable relatively to the latch means and adapted when the casing assumes a predetermined position to move under the force of gravity relatively to the latch means and strike a portion of the latch means at the end of such movement whereby to overcome the friction between the latch means and the second mentioned portion of the casing and allow movement of the latch means to inoperative position.

4. A projectile comprising an openable casing, latch means normally maintaining the casing closed, guide means carried by the latch means, and gravity actuated means movable along said guide means controlling the latch means.

RALPH W. HIPPEN.
